(57) **CLAIM**

The ornamental design for a bag, as shown and described.

DESCRIPTION

FIG. 1 is a front perspective view of the bag in a first embodiment;

FIG. 2 is a front elevation view of the bag of FIG. 1;

FIG. 3 is a top plan view of the bag of FIG. 1;

FIG. 4 is a bottom plan view of the bag of FIG. 1;

FIG. 5 is a left side elevation view of the bag of FIG. 1;

FIG. 6 is a rear elevation view of the bag of FIG. 1;

FIG. 7 is a right side elevation view of the bag of FIG. 1;

FIG. 8 is a front perspective view of the bag in a second embodiment illustrating the first embodiment in which a tab portion is folded against a body of the bag;

FIG. 9 is a front elevation view of the bag of FIG. 8;

FIG. 10 is a top plan view of the bag of FIG. 8;

FIG. 11 is a bottom plan view of the bag of FIG. 8;

FIG. 12 is a left side elevation view of the bag of FIG. 8; and, FIG. 13 is a right side elevation view of the bag of FIG. 8; and wherein a rear elevation view of the embodiment of FIG. 8 is the same as FIG. 6.
